WIRING DEVICE

Shirley R. Naysmith, Meriden, Conn., assignor to
 The Miller Company, Meriden, Conn., a corpora-
 tion of Connecticut

Application March 28, 1945, Serial No. 585,298

3 Claims. (Cl. 240—52)

1

The present invention relates to wiring devices, and is more particularly directed toward wiring devices adapted for use in outdoor lighting where the lighting equipment is to be supported from a horizontal conduit.

In some forms of outdoor lighting particularly signboard lighting it is customary to support a conduit from the signboard structure and have the conduit extend forwardly of the signboard structure to support the lighting equipment. The conduit opens at the rear into a suitable weather-proof fitting.

Lighting equipment used for this purpose typically employs a pendent lamp socket, a metal reflector with oblique angular opening and socket cover which extends up around the socket and is secured to the socket. The socket is usually provided with a fitting having a hexagonal head which holds the socket cover in locked position relative to the socket axis, and this fitting has threads for securing it to a conduit and for a lock nut which locks the socket cover in place. The devices heretofore available for securing the lighting equipment to the conduit and getting the wiring from the socket back through the conduit have been extremely cumbersome. It has required two men to put these parts together. There has been the hazard of twisting of wires, and difficulties have arisen because of the inability to readily orient the reflector relative to the signboard.

The present invention contemplates a construction well suited for this purpose wherein the entire assembly operation can be done by one person and the adjustment of the fixture to have its socket axis vertical and the reflector oriented in the proper direction is easily obtained.

The present invention contemplates providing the conduit with an angle shaped fitting having a flange adapted to be brought to position below the horizontal conduit, this flange carrying a locking ring. At the same time the fixture part of the construction employs an adaptor fitting for securing the socket cover and socket together and this adaptor fitting is externally threaded to fit the locking ring. Wiring can be readily completed and then the parts coupled together by one man using a wrench.

The accompanying drawings show, for purposes of illustrating the present invention, an embodiment in which the invention may take form, it being understood that the drawings are illustrative of the invention rather than illustrating the same.

In these drawings:

2

Figure 1 is a vertical sectional view with parts in elevation;

Figures 2 and 3 are horizontal sectional views taken on the line 2—2 and 3—3, respectively, of Figure 1; and

Figure 4 is a diagrammatic perspective view illustrating the use of the device.

A typical signboard is illustrated at 10 in Figure 4. Extending forwardly of the sign are conduits such as indicated at 11, 11. The further conduit 11 carries a lighting fixture indicated generally at 12, while a similar lighting fixture 12 is illustrated as being supported on the ground.

The lighting fixture 12 typically comprises an angle reflector 13, a socket cover 14 secured to the reflector; a lamp socket 15 adapted to carry a lamp 16 and a fitting 17 secured to the upper part of the socket. The fitting 17 has the usual hexagonal head 18 to fit the hexagonal upper end 19 of the socket cover. The fitting 17 may have the usual threads 20 employed for supporting such a fitting from a vertical conduit, but such threads are not necessarily present in the device embodying the present invention. The fitting 17 is threaded externally as indicated at 21 and an adaptor ring 22 is threaded down on to the fitting. This ring has a lower flange 23 which is brought against the top of the socket cover and is locked against unthreading from the fitting 17 by a lock screw 24. These parts may be assembled on the ground as indicated in Figure 4 and with wires 25 of sufficient length to reach back through the conduit 11.

The conduit 14 is provided with an elbow fitting 30 threaded at 31 on to the conduit and it has a flange 32 at the bottom. For convenience the bottom face of the flange is shown as horizontal and it may be provided with a groove 33 adapted to fit a bead 34 formed on the adaptor ring 22, this bead and groove providing a seepage stop. The flange 32 carries a hexagonal locking ring 35 threaded at 36 to fit the external threads 37 on the adaptor ring 22. In bringing the fixture to position it is merely necessary to carry the fixture up to the desired height, feed the wires up through the wiring space 38 in the elbow fitting 30 and back through the pipe or conduit 11. The fixture may be readily brought up into position so that the threads on the locking ring 35 can be engaged with the threads on the adaptor ring 22, the engagement of these threads being very similar to that which takes place when one puts together an ordinary pipe coupling. A single operative with a wrench can then tighten up the parts and make all adjustments so that

the axis of the socket is vertical and the reflector is turned up just the proper angle to direct the light toward the desired area of the signboard. The ring 35 is locked in place by a jam screw 40. The wiring is completed at the outlet box and support carried by the signboard in the usual way.

By having a stock of the special fittings contemplated by the present invention—elbow fitting, threaded ring and adaptor ring—the electrician can readily connect up other standard parts to provide the desired lighting equipment.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. An outdoor lighting device comprising a horizontal conduit, a relatively fixed elbow fitting threaded on the conduit and having a downwardly opening wiring passage and a bottom flange with annular upper and lower bearing surfaces, an inwardly flanged locking ring loosely but non-removably carried on the upper surface of the flange and having an internally threaded skirt, and a detachable lighting fixture assembly comprising a reflector having a socket cover with an internally extending flange, a lamp socket, an upwardly extending, externally threaded fitting secured to the lamp socket, and an adapter ring threaded on the socket fitting and bearing against the socket cover flange and having external threads received in the threads of the skirt of the locking ring to secure the

adapter ring on the skirt and against the lower surface of the flange on the elbow fitting.

2. A lighting device as claimed in claim 1 wherein the fixture assembly includes current supply wires secured to the socket and protruding through the socket carried fitting, the wires having a length to permit feeding them through the elbow fitting and conduit for connection at the other end of the conduit.

3. A lighting device as claimed in claim 1, wherein the reflector is asymmetric about the vertical axis of the threaded parts to produce a downwardly oblique beam, and having two set screws, one locking the adapter ring and socket carried fitting against relative rotation and the other locking the adapter ring and skirt against rotation whereby the reflector may be secured in adjusted position about said vertical axis to orient the beam.
